UNITED STATES PATENT OFFICE.

GEORGE E. LACKEY, OF NEW YORK, N. Y., ASSIGNOR TO INTERNATIONAL LACE CO.,
OF NEW YORK, N. Y., A CORPORATION OF NEW YORK.

DESIGN FOR A BEDSPREAD.

43,050.

Specification for Design. Patented Sept. 24, 1912.

Application filed July 18, 1912. Serial No. 710,263. Term of patent 3½ years.

To all whom it may concern:

Be it known that I, GEORGE E. LACKEY, a citizen of the United States, residing in the borough of Manhattan, in the city, county, and State of New York, have invented a new, original, and ornamental Design for Bedspreads, of which the following is a specification, reference being had to the accompanying drawing, forming part thereof.

The figure is a plan view of a bed spread, showing my new design.

I claim:

The ornamental design for a bed spread as shown.

GEO. E. LACKEY.

Witnesses:

C. W. KENNEKE,
GEO. C. COOK.
